United States Patent Office

Des. 215,220
Patented Sept. 16, 1969

215,220

COMBINED GAME TABLE, CABINET, AND RECORD PLAYER UNIT

Allen N. Eide, 2001 Winnetka Ave. N.,
Minneapolis, Minn. 55427

Filed Oct. 20, 1967, Ser. No. 9,086

Term of patent 14 years

Int. Cl. D6—01; D21—01, 04

U.S. Cl. D33—14

Fig. 1

Fig. 2

FIGURE 1 is a perspective view of a combined game table, cabinet and record player unit showing my design with the top in exploded position for convenience of illustration;

FIGURE 2 is an end elevational view taken from the left in FIGURE 1 and showing the top in place;

FIGURE 3 is a front perspective view showing the record player in open position; and

FIGURE 4 is a front perspective view showing the cabinet in open position.

The rear elevational view is substantially identical with the front view clearly shown in FIGS. 1, 3 and 4 with similar outline of the door or opening below the top of the table.

The dominant features of my design reside in those portions shown in full lines on the drawing.

I claim:

The ornamental design for a combined game table, cabinet and record player unit, as shown and described.

References Cited

UNITED STATES PATENTS

D. 112,970	1/1939	Voorhees	-----	D33—14
D. 133,435	8/1942	Gunder.	-----
D. 134,726	1/1943	Weber	-----	D33—14
D. 169,388	4/1953	Placke	-----	D33—14
D. 190,503	6/1961	Barron	-----	D33—14

OTHER REFERENCES

Radio Retailing, August 1937, p. 14, chair.

BRUCE W. DUNKINS, Primary Examiner